UNITED STATES PATENT OFFICE.

EMIL R. STASCH, OF CORNING, NEW YORK.

CHIMNEY-COWL.

SPECIFICATION forming part of Letters Patent No. 295,687, dated March 25, 1884.

Application filed September 3, 1883. (No model.)

To all whom it may concern:

Be it known that I, EMIL R. STASCH, a citizen of the United States of America, residing at Corning, in the county of Steuben and State of New York, have invented certain new and useful Improvements in Chimney-Cowls, of which the following is a specification, reference being had therein to the accompanying drawings.

10 My invention relates to an improvement in chimney-cowls; and it consists in the vertical smoke-cylinder A, the deflector B, open at bottom and partly open at top, and shield C, and in the construction and arrangement of the parts, substantially as hereinafter more fully specified.

In the drawings, Figure 1 is a side elevation, and Fig. 2 is a sectional elevation.

My chimney-cowl is designed not only to prevent smoking chimneys, but by increasing the chimney-draft to augment combustion; and to this end I construct a vertical smoke-cylinder, A, having the cylindrical deflectors B jointed to and opening into it on either side of its upper part, as shown, and rigidly secure therein shield C by ordinary means on a plane

longitudinal to the deflectors. The products of combustion as they arise in cylinder A impinge against the top of the shield, and are from thence deflected toward the openings E. It will be observed that this shield not only closes in part the top of cylinder A and prevents ingress of wind at that point, but that it deflects the wind down the deflector, and thus produces a vacuum-suction in the chimney and an increased draft.

Having thus described my invention, what I claim is—

A chimney-cowl composed of a cylindrical flue, A, two downwardly-projecting hollow arms, B B, and a deflecting-shield placed directly above the flue and composed of two inclined plates, each extending into the hollow arms B B and terminating at or near the level of the top of flue A.

In testimony whereof I affix my signature in presence of two witnesses.

EMIL R. STASCH.
